INVENTOR

UNITED STATES PATENT OFFICE.

FRED. H. BROWN, OF FORT WORTH, TEXAS, ASSIGNOR OF ONE-HALF TO
DE WITT C. PENDERY, OF SAME PLACE.

RAILWAY RAIL AND CHAIR.

SPECIFICATION forming part of Letters Patent No. 245,128, dated August 2, 1881.

Application filed May 31, 1881. (No model.)

To all whom it may concern:

Be it known that I, FRED. H. BROWN, of Fort Worth, in the county of Tarrant and State of Texas, have invented certain new and useful Improvements in Railway-Rails; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of one end of a rail with its chair embodying my improvement. Fig. 2 is a vertical cross-section of the same; and Fig. 3 is a perspective view of one of the intermediate chairs which support the rail between the ends or end chairs.

Similar letters of reference indicate corresponding parts in all the figures.

My invention contemplates an improvement in reversible railway rails and chairs, or supports for the same, as hereinafter more fully set forth, and particularly pointed out in the claim.

In the annexed drawings, A represents the rail, which is composed of a central flattened web or body, a, with straight parallel sides, and two flanges, b b, made with rounded heads, 30 and sharp shoulders, b', on their under side, which form right angles with the sides of the web or body a, along the middle line of which is a series of oblong bolt-holes, c. These rails are secured upon the ties by means of chairs, 35 each of which is composed of two plates, B B, which are bolted to opposite sides of the web a by bolts C, inserted through the bolt-holes c. The plates are fastened to the ties by spikes D inserted through the lateral wings or bottom flanges, d d, and are made with recesses e e, forming a sharp upper or inner corner, f, and rounded down to the projecting lip g at the lower inner end of the plate, which is flush with or forms a continuation of the flange d. The 45 curvature of the inner wall of the recess e is upon a longer radius than that of the rounded head or thread b, so that an open space, h, of a crescent shape will be left between the bottom head, b, and inwardly-projecting lips g g.

50 When the rail is placed in the chair and per squared shoulders, b' b', upon the squared bolted to the plates B B it will rest with its top flanges, i i, of the chair-plates, between

which an elastic packing, k, of rubber, leather, or other suitable material, may be placed to 55 form an elastic tread and deaden the noise of passing trains, especially where the track is laid in the streets or suburbs of towns or cities. By reference to Fig. 2 it will also be seen that the rail is hugged closely by the plates, except 60 under the lowermost part, b, where the open space h may be utilized for the passage of insulated telegraph or telephone wires laid along the track, which will be protected for their entire length by the rails A above. This space 65 also provides for the yielding of the rail where the elastic packing k is used.

The chairs which support the length of rail between its ends are only half the length of the end chairs, one intermediate chair being spiked 70 to each tie, while the end chairs span and are spiked to two successive ties. Otherwise their construction is substantially the same. The pair of plates B B of each chair are also exactly alike, and may be cast in the same mold. 75

It is obvious that to reverse the rails after the bolts C have been withdrawn, only the plates B on one side of the line of rails need be removed, leaving the series of plates on the opposite side remain bolted to the ties. After 80 the rail has been reversed the plates are replaced, bolted, and spiked in their former position.

I am well aware that it is not new to clamp railway-rails, reversible or otherwise, in chairs 85 composed of plates arranged opposite to one another, and recessed to conform to the shape of that part of the rail or rails which is clamped between them; hence I do not claim such construction broadly; but

90 What I claim as my improvement, and desire to secure by Letters Patent of the United States, is—

The combination of the reversible rail A and chair-plates B B, constructed and arranged as 95 described, so as to leave an open crescent-shaped space, h, below the middle part of the rail and above the inwardly-projecting lips g g, as shown, and for the purpose set forth.

In testimony that I claim the foregoing as 100 my own I have hereunto affixed my signature in presence of two witnesses.

FRED. H. BROWN.
